CALVIN N. COLPITTS, OF BOSTON, MASSACHUSETTS, ASSIGNOR TO AMERICAN SHADE MACHINE COMPANY, OF BOSTON, MASSACHUSETTS, A CORPORATION OF MAINE.

MACHINE FOR CUTTING AND CREEASING SHEET MATERIAL.

1,079,542.

Specification of Letters Patent.

Patented Nov. 25, 1913.

Application filed December 20, 1910. Serial No. 598,388.

To all whom it may concern:

Be it known that I, CALVIN N. COLPITTS, a citizen of the United States, residing at Boston, county of Suffolk, and State of Massachusetts, have invented an Improvement in Machines for Cutting and Creasing Sheet Material, of which the following description, in connection with the accompanying drawing, is a specification, like characters 10 on the drawing representing like parts.

This invention relates to a machine for cutting and folding sheet material and is in the nature of an improvement on the device shown in my Patent No. 931,996, dated August 24, 1909. This patent shows a machine adapted to measure off a certain length of sheet material and to sever said length from the body of material, and at the same time to form one or more creases in the material 20 along lines parallel to the severed edge. The machine of said patent is especially designed for cutting off and creasing lengths of shade material to form window shades, and the creasing of the shade material is for the purpose of facilitating the folding thereof to 25 form the hem at the lower edge of the window shade.

The present improvements relate particularly to the means for cutting and creasing 30 the sheet material and the means for measuring the length which is to be cut off.

The improvements relative to the creasing of the sheet material have for their object to provide a construction wherein the 35 material may be creased either on the top or the bottom according to the character of hem which it is desired to make, and the improvements relating to the measuring device are for the purpose of simplifying the 40 construction and reducing the number of parts.

I will first describe one embodiment of my invention and then point out the novel features thereof in the appended claims.

Referring now to the drawings wherein I 45 have illustrated a selected embodiment of my invention which is sufficient to disclose the principle thereof, Figure 1 is a fragmentary view of the side of a machine such as shown in my patent, said view showing my improved cutting, creasing and measuring device in side elevation; Fig. 2 is an enlarged sectional view through the measuring device on the line $x-x$, Fig. 1; Fig. 3 is a

front view of the mechanism shown in Fig. 1; Fig. 4 is an enlarged side view of the cutting and creasing device with a part of the cutting wheel broken out; Fig. 5 is a top plan view of Fig. 4; Fig. 6 is a section on the line y , Fig. 7; Fig. 7 is a section on the line $a-a$, Fig. 5; Figs. 8, 9 and 10 show three different styles of hems that are used in the manufacture of window shades; Figs. 11, 12 and 13 show the manner in which the sheet material is creased to form the hems; Fig. 14 shows the arrangement of creasing wheels to form the creases shown in Fig. 12; Fig. 15 shows an arrangement of creasing wheels to form the creases shown in Fig. 13; Fig. 16 is a diagrammatic view showing the manner in which the cutting wheel is moved angularly against the shearing edge during its operation; Fig. 17 is an enlarged section through the measuring device on the line $b-b$, Fig. 1.

As stated above, the devices herein illustrated are designed to be used in connection with a machine such as that shown in my Patent No. 931,996. This machine comprises a frame supporting a table over which the sheet material is fed, a feeding drum sustained by the frame and adapted to feed sheet material over the table, a measuring device which cooperates with the means for rotating the drum to stop the rotation of the drum when the desired length of sheet material has been fed off, and a pocket or receptacle into which the severed length of sheet material is rolled up after the edges thereof have been folded. The table over which the sheet material is drawn by the feeding drum is provided with a V-shaped track and the knife for severing the lengths of material is mounted on a carriage provided with creasing wheels which roll over said track and thereby form creases in the material adjacent the severed edge at the same time that the knife operates to sever the length of material. Since the present invention, however, relates only to the severing, creasing and measuring devices, I have not deemed it necessary to show in detail the entire machine, but have contented myself with illustrating in Fig. 1 a portion of the frame 3 and a portion of the feeding drum 4 which is rotatably sustained by the frame and which operates to feed the sheet material over the creasing table 5 on which

the knife-supporting carriage and creasing wheels run. The drum 4, a part of which is illustrated in Fig. 1, may have the same construction and operate in the same way as 5 the feeding drum of said patent, and for further explanation of its operation reference to said patent may be had.

The creasing table 5 is supported by the frame 3 and is somewhat similar to that 10 shown in my said patent, but in the present invention it is designed so that creases on either side of the material can be made, as will be more fully hereinafter described. Associated with the creasing table 5 is a 15 shearing member 6 formed with a shearing edge 7 which extends from one side of the machine to the other and with which a rotary knife 8 co-operates to sever the measured lengths of material. This knife 8 is 20 sustained by a carriage 9 adapted to be moved back and forth across the creasing table, all as described in said patent, and during such movement the knife 8 co-operates with the shearing edge 7 to sever the 25 material. The means for moving the carriage will be presently described.

In order to provide for creasing the material on either the top or bottom side, the creasing table 5 is made with ridges 10 and 30 grooves 11 which are parallel to each other and extend the length of the table from one side of the machine to the other, and the carriage is provided with two sets of creasing wheels, the creasing wheels of one set 35 being in the nature of female creasing wheels and having grooves in their periphery to fit over the ridges 10, and the other creasing wheels being in the nature of male creasing wheels and having a shape at their 40 periphery to fit into the grooves 11. I have herein shown two female creasing wheels 12 and 13 and two male creasing wheels 14 and 15. These wheels are all sustained by a 45 spindle 16 which is mounted in the carriage 9 and provision is made whereby any of the wheels may be brought into engagement with the track, depending whether the material is to be creased on the top or the bottom side. There are various ways in which 50 these wheels might be mounted so that the different wheels can be brought into operative engagement with the track. The drawings show one simple construction wherein the male creasing wheels are mounted on eccentric portions of the spindle 16 so that by turning the spindle through 180° more or less, said wheels may be brought 55 into engagement with the track and the other wheels lifted out of engagement. 60 This, however, is only one of several ways in which this end might be accomplished without departing from the invention.

As herein shown, the creasing wheels 12 and 13 are loosely mounted on the spindle 65 16 concentrically thereof. The creasing

wheel 14 is loosely mounted on an eccentric portion 17 of the shaft, which eccentric portion can conveniently be made by securing to the shaft an eccentric collar. The creasing wheel 15 is also eccentrically mounted on the spindle 16 by being loosely sustained on an eccentric collar 18. When the spindle is in the position shown in Fig. 7, the creasing wheels 14 and 15 are elevated above the creasing wheels 12 and 13, while if the 70 shaft is turned through 180°, the creasing wheels 14 and 15 will be depressed below the creasing wheels 12 and 13.

The knife 8 is shown herein as being driven from the creasing wheel 12, and for 75 this purpose said wheel has extending therefrom a pin 19 that enters an aperture 20 formed in the knife, said knife being loosely sustained on the spindle 16 and being acted on by a suitable spring 21 which tends to 80 hold it against the shearing edge 7. This spring is backed by a collar 22 loosely mounted on the spindle and resting against a ball bearing 23 which is situated between 85 it and the fixed collar 24.

In order to better understand the operation 90 of the creasing wheels I will refer now to Figs. 8, 9 and 10, which show different styles of hems that are used in window shades. In Fig. 8 is shown a style of hem wherein the 95 main body of the shade 25 is folded back on itself at 26 to form the portion 28, and then is folded again at 27 to form the outer portion 29, said portion 29 being folded at 30 so that edge 31 of the material lies between the portions 28 and 29. The hem is finished by sewing the edges of the fold by two lines of stitching 32, 33. A hem of this 100 type is desirable on so-called duplex shade material in which the opposite sides are of 105 different colors, for each side of the hem shows the same color as the shade material. In order to make a hem of this construction the sheet material has to be creased as shown in Fig. 11, that is, it is provided on its upper 110 side with the crease 34 and between this crease and the edge of the material are two other creases 35 and 36 on the under face of the material. After the material has been creased in this way, the portion 31 is folded 115 against the part 29 along the crease 36, and the material is then folded again along the crease 35 to bring two plies or portions 31, 29 against the portion 28 and the material is then folded again along the crease 34, but 120 in a reverse direction from the other fold, to complete the hem shown in Fig. 8. To 125 crease the material for forming this hem, therefore, necessitates forming two creases on the under side and one crease on the upper side.

In Fig. 9 is shown a simpler hem of the ordinary type in which the material is merely folded back on itself at 37 and the edge of the material is then folded again at 130

38 so that no raw edge of the material is exposed. In this case the hem is formed on the under face of the material 25 and to form a hem of this nature it is necessary to 5 form two creases 35 and 36 only in the under face of the material.

The hem shown in Fig. 10 is similar to that shown in Fig. 9 except that it is formed on the upper face of the material and to 10 crease the material for forming this hem involves the formation of two creases 39 and 40 on the upper face of the material, as shown in Fig. 13.

The female wheels rolling over the ridges 15 10 serve to form the creases 35 and 36 in the under face of the material, while the male creasing wheels 14 and 15 moving in the grooves 11 serve to form the creases 34, 39 and 40 on the upper face of the material.

20 In order to form the creases shown in Fig. 11 the parts are adjusted as shown in Fig. 7, that is, the female creasing wheels 12 and 13 are arranged to rest on two of the ridges 10, the creasing wheel 14 is elevated 25 out of contact with the creasing table by proper adjustment of the spindle 16 and the creasing wheel 15 is arranged to engage a special groove 11^a formed on the table, which groove is situated at a higher level 30 than the grooves 11.

When the length of sheet material has been drawn over the creasing table, the carriage is drawn across said table and during its travel the creasing wheels 12, 13 and 15 35 will form the creases 36, 35 and 34 in the material, as shown in Fig. 11, and at the same time the knife 8 coöperating with the shearing edge 7 will sever this measured length of material, it being understood that 40 the knife 8 rotates and derives its rotation from the rotary movement of the creasing wheel 12. If, on the other hand, the material is to be creased in the manner shown in Fig. 12, then the creasing wheel 15 is thrown 45 out of operation, and this is done by adjusting said wheel longitudinally of the shaft 16 into the position shown in Fig. 14. Since the groove 11^a is at a higher level than the other grooves 11, it will be seen that when 50 the creasing wheel 15 is thus adjusted longitudinally of the spindle, it will not contact with the bottom of the groove 11, but will be spaced therefrom, as shown in Fig. 14. This longitudinal movement of the creasing 55 wheel 15 may be secured in various ways without departing from my invention. I have herein shown the eccentric collar 18 as splined to the spindle 16 so that it can move longitudinally thereof, but cannot rotate 60 thereon, and the creasing wheel 15 is mounted on the collar so that it can turn freely thereon but cannot move longitudinally thereof. This can be readily accomplished by the U-shaped key 41 which slides back 65 and forth in a groove 42 in the spindle and

the arms of which embrace the collar 18 and also a portion of the hub 43 of the creasing wheel.

To form the creases shown in Fig. 13, the spindle 16 is turned through 180° thereby 70 depressing the male creasing wheels 14 and 15 relative to the female creasing wheels 12 and 13 so that the weight of the carriage will be supported on the male creasing wheels, while the female creasing wheels are 75 elevated out of contact with the creasing table, all as shown in Fig. 15. When the carriage with the creasing wheels thus adjusted is passed over the creasing table, the material will be creased on the upper side, 80 as shown in Fig. 13.

For turning the spindle 16 I propose to employ the construction shown in Fig. 6 and which comprises a pin 430 projecting laterally from the spindle and having on its 85 end a movable locking head 44 that incloses a spring 45. This locking head is provided with a projection 46 shown in dotted lines Fig. 6 that is adapted to enter either one of two notches 47 formed in the carriage 9. Said carriage is provided with the slot 48 in 90 which the pin 430 works. By withdrawing the locking head 44 to disengage the projection 46 from the notch, said arm may be swung in the slot to turn the spindle from 95 one position to the other as desired.

The creasing wheel 13 may be adjusted longitudinally of the spindle to coöperate with any one of the ridges 10 according to the width of hem desired.

For moving the carriage 9, back and forth across the track, I have provided the mechanism shown in Figs. 1 and 3 and which comprises a driving wheel 50 supported in a stand 51 carried by the frame 52 and over which runs a sprocket chain 54 that extends to the opposite end of the machine and passes around an idler 53. The ends of the sprocket chain are fastened to the carriage at 55 and 56, respectively, so that by turning the driving wheel 50 by means of the handle 57 the carriage may be drawn back and forth across the track. The frame 53 is provided with a guiding track 58 and the carriage is shown as having two arms 59 and 60 extending therefrom, each of which has a guide roller 61 that runs on the guiding track 58. Suitable spring-pressed buffers 62 at each end of the frame 52 serve to limit the movement of the carriage by engagement with the guide wheels 61. The arm 60 is preferably made in two sections that are hinged together at 65 and which can be adjusted relative to each other by the adjusting screw 64, the purpose of 115 this construction being to take up any lost motion between the carriage and the tracks on which it runs.

In order that the cutting knife 8 may work properly, it is essential that the ad- 130

vancing or forward edge thereof should always be held against the shearing edge 7 and to provide for this I have employed a construction whereby the pull on the 5 sprocket chain which gives the carriage its motion will tend to turn the knife angularly slightly relative to the shearing edge, so that in whichever direction the carriage moves, a clean cut will be made. The ends 10 of the sprocket chain 54 are connected to two arms 67 68 that are secured to an arm 69 of a yoke-shaped member 70 that is pivoted to the carriage at 71. The arms 72 of this yoke-shaped member are situated between the cutting knife 8 and the creasing 15 wheels and are provided with pins 73 which are situated nearly on a horizontal diametrical line. In Fig. 16 I have shown in diagram the way in which this construction 20 operates, although the showing is, of course, somewhat exaggerated. When the chain is pulling on the arm 67 in the direction of the full line arrow Fig. 16, this pull will tend to turn the yoke member 70 about its 25 pivot 71 so as to bring it into the full line position and to force the left-hand pin 73 against the knife 8. The tendency of these forces is to turn the knife angularly slightly so that the advancing edge or the right-hand edge in Fig. 16 is pressed more firmly 30 against the shearing edge 7. When the carriage is moved in the opposite direction, however, or in the direction of the dotted line arrow, the parts are swung in the 35 dotted line position and the tendency of the yoke is to crowd the knife 8 angularly in the opposite direction so that the edge which is at such time the advancing edge will be crowded toward the shearing edge 7. 40 It will be understood, of course, that there is not as great an angular movement of the knife as indicated in Fig. 16, but that this construction merely tends to press the advancing edge of the knife against the shearing edge 7 in whichever direction the carriage is moved.

The arm 67 of the yoke is shown as provided with adjustable stop screws 74 which are adapted to engage a tongue 75 mounted 45 on the carriage and thereby limit the swinging movement of the yoke 70.

In the operation of the device the carriage with the cutting knife and creasing wheels will be moved from one end of the track to the other thereby to sever and crease one 50 length of material and while the carriage remains at the end of the track a fresh length of sheet material is drawn forward and measured and then the carriage is moved back to its initial position thereby 55 severing and creasing the second length of material. With the present invention, therefore, one pass of the carriage across the table is sufficient to sever and crease any length 60 of material.

I have shown in Figs. 1, 2 and 17 a measuring device which is well adapted to be used in connection with my apparatus for measuring and indicating the desired length of shade material. This measuring device 70 comprises a measuring wheel 83 having a friction tread 84 and adapted to rest on the shade material 25, said wheel operating over a groove 920 in the frame. The wheel 83 is journaled in a frame 85 and has a pinion 75 86 rigid therewith which meshes with gear teeth 87 on a dial member 88, said member being loosely mounted on a stud 89 and having connected thereto one end of a return spiral spring 90. The dial member 88 has 80 rigid therewith a pinion 94 which meshes with and drives a gear 95 carrying a stop pin 93 adapted to rest against a fixed stop pin 940. The dial member 88 has graduation marks on its face arranged to indicate 85 any desired units of length, such, for instance, as yards or feet. The dial is read by means of a fixed indicator or pointer 92. When the shade material is drawn under the wheel 83 the dial will be rotated and when 90 said dial indicates the proper length the feeding of the shade material will be stopped and the cutting knife will then be operated, as above described, to sever the length and when this severed length has been pulled out 95 from under the measuring device the spring 90 operates to return it to its zero position, as shown in Fig. 1.

79 and 80 designate guide rolls between which the material is fed to the guiding 100 knife 8. The guide roll 79 is sustained in a swinging bracket 81 which is pivoted to the frame at 99 and to which is connected a handle 82 by which the roll 79 may be swung toward and from the roll 80.

I have provided herein a gripping device to grip the material adjacent the point where the guiding knife operates so as to prevent the material from drawing back after any length has been severed. This gripping device is in the form of a gripping rib 97 which extends along the bed of the machine and a swinging gripping member 101 which is pivotally connected to the swinging bracket 81 and has connected thereto a suspender 98 which is suspended from the frame at 100, said suspender preferably being provided with a slot at its upper end to permit a slight vertical movement. The weight of the gripping member 101 resting 110 on the material which passes between it and the gripping member 97 is sufficient to prevent the material from drawing back and the pin-and-slot connection between the suspender and the frame permits the gripping member 101 to drag over the rib 97 without binding whenever the bracket 81 is operated.

While I have illustrated one embodiment of my invention, I do not wish to be limited to the constructional details shown.

Having fully described my invention, what I claim as new and desire to secure by Letters Patent is:—

1. In a machine for cutting and creasing sheet material, the combination with means to feed sheet material, of means to cut said material transversely to the direction of feed, and means to form creases in either side of said material at will. 5
2. In a machine for cutting and creasing sheet material, the combination with means to feed sheet material, of means to cut said material transversely to the direction of feed, and means associated with the cutting means 10 to form creases in either side of said material at will.
3. In a machine of the class described, the combination with means to feed sheet material, of means to form creases transversely 15 of the length of the material in either or both sides thereof at will.
4. In a machine of the class described, the combination with means to feed sheet material, of means to form creases transversely of the length of the material in either side thereof at will. 20
5. In a machine of the class described, the combination with a creasing track over which sheet material may be drawn, of a carriage 25 movable on said track and provided with male and female creasing wheels, and means to bring either of said wheels into operative engagement with the track. 30
6. In a machine of the class described, the combination with a creasing track having 35 ridges and grooves, of a female creasing wheel adapted to roll over one of the ridges thereby to make a crease in the under side of the sheet material, a male creasing wheel 40 adapted to roll in a groove to form a crease in the upper side thereof and means sustaining said wheels for adjustment toward and from each other. 45
7. In a machine of the class described, the combination with a creasing track having ridges and grooves, of a female creasing 50 wheel adapted to roll over the ridges thereby to make a crease in the under side of the sheet material, a male creasing wheel adapted to roll in the groove to form a crease in the upper side thereof, and means to place either of said wheels in operative position. 55
8. In a machine of the class described, the combination with a creasing track having ridges and grooves, of a plurality of female 60 creasing wheels adapted to roll over parallel ridges thereby to make creases in the under-side of the material, a plurality of male creasing wheels adapted to roll in the grooves thereby to form creases in the upper side of the material, and means to shift the wheels into and out of operative position. 65
9. In a machine of the class described, the combination with a creasing track having ridges and grooves, of a plurality of female 70 creasing wheels adapted to roll over parallel ridges thereby to make creases in the under-side of the material, a plurality of male creasing wheels adapted to roll in the grooves thereby to form creases in the upper side of the material, and means to move the female creasing wheels into operative position and simultaneously move the male creasing wheels out of operative position. 75
10. In a machine of the class described, the combination with a creasing track having ridges and grooves, of a plurality of female creasing wheels adapted to roll over parallel ridges thereby to make creases in the under-side of the material, a plurality of male 80 creasing wheels adapted to roll in the grooves thereby to form creases in the upper side of the material, and means to move the female creasing wheels into and out of operative position and simultaneously move the male 85 creasing wheels out of and into operative position. 90
11. In a machine of the class described, the combination with a creasing table having ridges and grooves, of means to draw sheet material over the table, a carriage movable on the table in a direction of the grooves, two sets of creasing wheels on the carriage, and means to bring the wheels of either set into engagement with said track. 95
12. In a machine of the class described, the combination with a creasing table having ridges and grooves, of means to draw sheet material over the table, a carriage movable on the table in the direction of the grooves, a spindle rotatably sustained by the carriage and provided with an eccentric, a male and a female creasing wheel on said spindle, one of said wheels being mounted on said eccentric portion, and means to turn the spindle 100 to bring either wheel into engagement with the track. 105
13. In a machine of the class described, the combination with a creasing table having ridges and grooves and a shearing edge, of means to draw sheet material over said table, a carriage movable on the table in the direction of the grooves, a spindle rotatably sustained by the carriage and provided with an eccentric portion, a male and a female creasing wheel on the spindle, one of said wheels being mounted on the eccentric portion, means to turn the spindle to bring either wheel into engagement with the track, and a cutter sustained by the spindle and coöperating with the shearing edge. 110 115
14. In a machine of the class described, the combination with a table having a shearing edge, and means to feed sheet material over said table, a carriage movable back and forth across the table, a rotary cutter on said carriage, means to operate the cutter on each pass of the carriage in either direction, and means tending to press the cutter angularly in one direction relative to 120 125 130

- the shearing edge as the carriage moves in one direction and to press said cutter angularly in the other direction relative to the shearing edge whereby the carriage moves 5 in the reverse direction.
15. In a machine of the class described, the combination with a table having a shearing edge, of a carriage, means to move the carriage back and forth across the table, a 10 spindle carried by the carriage, a rotary cutter mounted on said spindle, but capable of a slight angular movement relative to said spindle, and means to give said cutter such angular movement thereby to press the advancing edge of the cutter toward the shearing edge as the carriage moves.
16. In a machine of the class described, the combination with a table having a shearing edge, of a carriage movable across the 20 table, a spindle sustained by said carriage, a rotary cutter having an opening through which said spindle extends, said opening being larger than the spindle, means connecting the cutter with the spindle whereby 25 rotation of the spindle rotates the cutter, and means to turn the cutter angularly relative to the spindle as the carriage moves thereby to press the advancing edge of the cutter toward the shearing edge.
- 30 17. In a machine of the class described, the combination with a table having a shearing edge, of means to feed sheet material over said table, a carriage movable across the table, a spindle sustained by the carriage 35 and rotatable as the carriage moves, a rotary cutter flexibly mounted on the spindle but rotatable therewith, carriage-propelling mechanism, and means operated thereby to move the cutter relatively to the spindle 40 thereby to press the advancing edge of the cutter toward the shearing edge.
18. In a machine of the class described, the combination with a table having a shearing edge, of means to feed sheet material 45 over the table, a carriage movable across the table, a rotary cutter on the carriage, carriage-propelling mechanism adapted to move the carriage in either direction, and means operated thereby to press the advancing edge of the cutter toward the shearing edge during each movement of the carriage. 50
19. In a machine of the class described, the combination with a table having a shearing edge, of means to feed sheet material over the table, a carriage movable across 55 the table, a rotary cutter mounted on the carriage and coöperating with the shearing edge, a member pivoted to the carriage and adapted to engage the rotary cutter, and carriage-propelling mechanism connected to 60 said pivoted member at a point out of line with its pivotal axis whereby the drag of the carriage on the propelling mechanism tends to press the advancing edge of the cutter toward the shearing edge. 65
20. In a device of the class described, the combination with a table, of means to draw sheet material over said table, a cutter movable across the table to sever a length of sheet material, a gripping rib adjacent the 70 path of movement of the cutter, and a pivoted gripping member loosely resting on said rib to engage the material passing thereover, thereby to prevent it from backward movement. 75
21. In a machine for cutting and creasing sheet material, the combination with means to feed sheet material, of creasing means for forming creases in said material transversely thereof, and means to adjust said 80 creasing means to form creases on either side of the material.
22. In a machine of the class described, the combination with means to feed sheet material, of crease-forming means including 85 two creasers, one to form creases on each side of the material, and means to render either creaser operative.
23. In a machine of the class described, the combination with means to feed sheet 90 material, of two creasing wheels, one to form a crease on each side of the material, and means to place either creasing wheel in operative position.
- In testimony whereof, I have signed my 95 name to this specification, in the presence of two subscribing witnesses.
- CALVIN N. COLPITTS.
